CLAIM

The ornamental design for a cart with a vacuum cleaner, as shown and described.

DESCRIPTION

FIG. 1 is a top perspective view of a cart with a vacuum cleaner;

FIG. 2 is a front view;

FIG. 3 is a side elevation view;

FIG. 4 is a back view;

FIG. 5 is a side elevation view of the side opposite of that shown in FIG. 3;

FIG. 6 is a top view; and,

FIG. 7 is a bottom view.

The portions shown in broken lines of FIGS. 1-7 are for illustrative purposes only and form no part of the claimed design.
